(57) **CLAIM**

The ornamental design for a bottle holder, as shown and described.

DESCRIPTION

FIG. 1 is a top, front, right perspective view of a bottle holder, showing our new design;

FIG. 2 is a bottom, rear, left perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a top, front, right perspective view of the bottle holder of FIG. 1, shown in a condition of use.

In FIG. 9, the broken lines depict environmental subject matter only and form no part of the claimed design.

1 Claim, 9 Drawing Sheets
